UNITED STATES PATENT OFFICE.

DANA G. HADLEY, OF WEST NEWBURY, MASSACHUSETTS.

INVALID'S CHAIR.

1,219,295.

Specification of Letters Patent.

Patented Mar. 13, 1917.

Application filed September 23, 1914. Serial No. 863,157.

To all whom it may concern:

Be it known that I, DANA G. HADLEY, a citizen of the United States, residing at West Newbury, in the county of Essex and 5 State of Massachusetts, have invented certain new and useful Improvements in Invalids' Chairs; and I do hereby declare the following to be a full, clear, and exact description of the invention, such as will enable others skilled in the art to which it app- 10 pertains to make and use the same.

This invention comprehends certain new and useful improvements in invalids' chairs and has for its primary object to provide a 15 device of this character which will be of extremely simple construction and operation as well as highly efficient in use, and which will be of such form that the chair may either be used as a rocking chair or as a 20 roller chair, as desired.

The invention has for another object to provide a chair of this character which will be provided with improved and novel means for propelling the chair, the hands being 25 used for operating the propelling mechanism forming the ends of the arms of the chair.

The invention has for a further object to provide propelling mechanism composed of 30 the minimum number of parts of such form that the operating gear may be readily thrown into engagement with the operated gear, or out of engagement with the same, as desired.

With these and other objects in view as will become more apparent as the description proceeds, the invention consists in certain novel features of construction, combination and arrangement of parts as will be 35 hereinafter more fully described and claimed.

For a complete understanding of my invention, reference is to be had to the following description and accompanying drawings, in which—

Figure 1 is a side elevation of the complete device,

Fig. 2 is a top plan view thereof,

Fig. 3 is an enlarged detail view of the 50 operating gear and operated gears in engagement with one another, said view also

showing the clutch mechanism by dotted lines, and

Fig. 4 is an enlarged detail section on the plane of line 4—4 of Fig. 1, looking in the 55 direction indicated by the arrow.

Referring in detail to the drawings by numerals, 1 designates the rocking chair which has its rockers 2 provided in their curved under sides with rack teeth 3 for engagement with similar teeth 4 on the upper faces of the side rails 5^a of the platform 5 upon which the rocking chair is mounted. The platform is provided at its rear end with rearwardly extending and upwardly 60 curved supporting brackets 6, to the upper free ends of which are pivoted the supports 7 of caster wheels 8. These wheels support the rear end of the platform.

It will be understood that the inter-mesh- 70 ing teeth 3 and 4 will prevent longitudinal movement of the rocking chair 1 with relation to the platform 5 when the chair is being rocked or when the device is being propelled.

At the outer ends of the arms 9 of the rocking chair 1 there are hand wheels 10, which hand wheels are keyed to the inner ends of shafts 11. The shafts 11 are journaled in and extend laterally from the upper 80 ends of the bracket arms 12 which are secured to and rise vertically from the side bars 12^a of the seat frame 12^b of the rocking chair. These shafts have keyed to their outer ends sprocket wheels 13 around which pass 85 sprocket chains 14 which also pass around sprocket wheels 15 keyed to the outer ends of the shafts 16. The shafts 16 are journaled in and extend laterally from the lower 90 ends of bracket arms 17 which are secured to and extend downwardly and rearwardly from the side bars 12^a.

A gear wheel 28 is splined upon each shaft 16 between one of the bracket arms 17, and one of the sprocket wheels 15. The gear 95 wheels 28 are provided with clutch faces 26 for engagement with clutch faces 27 of the sprocket wheels 15. The gear wheels 28 also have extended hubs 24 provided with annular grooves 25 for the reception of the lower forked ends 22 of shifting levers 18. These levers are pivoted between their ends

upon pins 19 carried by the ears 21 of brackets 20 secured to the outer sides of the side bars 12^a. By means of these levers either gear wheel 28 may be thrown into or out of 5 clutching engagement with its companion sprocket wheel 15.

- The front end of the platform 5 is supported by propeller wheels 30 which are independently journaled upon the platform 5 by means of hollow shafts 30^a. The wheels 10 are fixed to the shafts 30^a, and the latter are journaled in and extend outwardly from bearing brackets 32, which are secured to and extend upwardly from the side rails 5^a. 15 As an additional support for the shafts 30^a, there is provided a rod 31, which is mounted in the shafts and which is held positioned by cap nuts 33. It is to be understood that the shafts 30^a are mounted for rotation independently of each other and the rod 31. 20 Gear wheels 29 are fixed to the shafts 30^a and mesh with the gear wheels 28 when the latter are in clutching engagement with the sprocket wheels 15.
- 25 As the bearing brackets 32 are located outside of the rockers 2, they prevent the chair 1 from moving laterally off the platform 5.

When it is desired to rock the chair, the 30 occupant moves the gear wheels 28 out of clutching engagement with the sprocket wheels 15. When it is desired to propel the chair, the gear wheels 28 are thrown into clutching engagement with the sprocket 35 wheels 15 by means of the shifting rods 18, and power is transmitted to the propelling wheels through the medium of the hand wheels 10. As the propelling wheels are mounted for independent rotation and as the 40 operating mechanism for the propelling wheels may be independently operated, it is only necessary when it is desired to turn the device to hold one propelling wheel against rotation by the hand wheel connected thereto and rotate the other propelling wheel by the other hand wheel. The propelling wheel held against rotation will act as a pivot about which the device will be turned by the 45 propelling wheel being operated. When the chair is being operated as a vehicle, there is secured to the rear side A a hook 3' and an eye 4' is secured to rockers 2 to hold the chair against rocking off the platform when being propelled as a vehicle.

55 While I have shown and described the preferred embodiment of my invention, it will be understood that minor changes in details of construction, combination and arrangement of parts may be made without departing from the spirit and scope of the invention as claimed, or sacrificing any of the advantages thereof.

What is claimed is:—

- 60 1. A device of the class described comprising a platform, a rocking chair mounted

upon said platform, means for preventing longitudinal movement of the rockers upon the platform, casters mounted in the rear of the platform, surface engaging wheels mounted in the front of the platform, and 70 means for rotating the surface engaging wheels independently of each other.

2. A device of the class described comprising a platform, surface engaging wheels for said platform, casters for the rear end of the 75 platform, a rocking chair mounted upon the platform, means for supporting said surface engaging wheels, gear wheels mounted upon said supporting means and connected with said surface engaging wheels to rotate with 80 the latter, hand wheels carried by said chair, operative connection between the hand wheels and the gear wheels, and means for disconnecting the hand wheels from said gear wheels when desired so that the 85 engaging wheels may be independently rotated.

3. A device of the class described comprising a platform, surface engaging wheels for said platform, a shaft for said surface engaging wheels, gear wheels mounted upon said shaft, a chair mounted upon said platform, hand wheels, carried by said chair, shafts supported beneath said chair, connection between said shafts and said hand 90 wheels to operate the surface engaging wheels, gear wheels carried by said shafts and engaging with the gears mounted upon the first mentioned shafts, and means for disconnecting the second mentioned gear 100 wheels from the first mentioned gear wheels.

4. A device of the class described comprising a platform, surface engaging wheels for said platform, a chair mounted upon said platform and adapted to rock upon the same, 105 means for preventing longitudinal movement of said chair upon said platform, a shaft carried by said platform, said surface engaging wheels keyed upon said shaft and adapted to rotate freely therewith, gear 110 wheels mounted upon said shaft which are connected with surface engaging wheels, operating means carried by said chair and engaging with said gear wheels, and means for disengaging said operating means permitting independent rotation of the surface 115 engaging wheels.

5. A device of the class described comprising a platform, a rocking chair mounted upon said platform, means for preventing movement of said chair longitudinally upon said platform, a shaft mounted upon said platform, surface engaging wheels mounted upon said shaft beneath the chair, gear 120 wheels connected with said surface engaging wheels, stub shafts mounted upon said chair, gear wheels mounted upon said stub shafts, said last mentioned gear wheels being normally engaged by the first mentioned gear 125 wheels, hand wheels mounted upon the chair, 130

connection between said hand wheels and the second mentioned gear wheels to rotate the same when said gear wheels are engaged by the first mentioned gear wheels, and
5 means mounted upon the chair for disengaging the second mentioned gear wheels from the first mentioned gear wheels.

In testimony whereof I affix my signature in presence of two witnesses.

DANA G. HADLEY.
